UNITED STATES PATENT OFFICE.

WILLIAM C. WINFIELD, OF WARREN, OHIO, ASSIGNOR TO THE WINFIELD MANUFACTURING COMPANY, OF SAME PLACE.

DESIGN FOR A CAN.

SPECIFICATION forming part of Design No. 22,515, dated June 6, 1893.

Application filed April 6, 1893. Serial No. 469,365. Term of patent 7 years.

To all whom it may concern:

Be it known that I, WILLIAM C. WINFIELD, a citizen of the United States, and a resident of Warren, in the county of Trumbull and State of Ohio, have invented and produced a new and original Design for Can-Tops, of which the following is a full, clear, and exact description, reference being had to the drawings making part of this specification.

In the accompanying drawings, Figure 1 is a plan view of a can as embodied in my new design of can, and Fig. 2 is a side elevation of the can.

A represents the top of the can. This top has a surface which is fashioned above its edge or rim into the form of a dome, or dome shape, as seen at —2—, and above this dome is a flat top bounded by the circular shoulder line —3—, which describes the termination

of the dome proper. Then as an offset to the ²⁰ design having this primary feature I have provided flutes —4— which start from about the base of the dome and narrow toward their top but deepen as they rise and terminate in the flat surface of the top above the dome and ²⁵ back from the center thereof. This gives the surface of the partly dome shape and partly flat can top a fluted and ribbed appearance and makes altogether a distinguishing and ³⁰ novel design.

Having thus described my invention, what I claim as new, and desire to secure by Letters Patent, is—

The design for a can as described and shown.
WILLIAM C. WINFIELD.
